[57] CLAIM

The ornamental design for a weighted holder for a liquid container, as shown and described.

DESCRIPTION

FIG. 1 is a perspective view of the weighted holder for a liquid container showing my new design;

FIG. 2 is a side elevational view thereof, the remaining sides being identical;

FIG. 3 is a top plan view thereof; and,

FIG. 4 is a bottom view thereof.

FIG.1

FIG. 2

FIG. 3

FIG. 4
